CLAIM

The ornamental design for an exterior surface of rear wheel unit for a motorcycle to tricycle conversion kit, as shown and described.

DESCRIPTION

FIG. 1 is a perspective view of an exterior surface of rear wheel unit for a motorcycle to tricycle conversion kit showing our new design;

FIG. 2 is a right side elevation view;

FIG. 3 is a left side elevation view;

FIG. 4 is a front elevation view;

FIG. 5 is a rear elevation view; and,

FIG. 6 is a top plan view.

The broken lines shown in all view of the drawing are for illustrative purposes only and form no part of the claimed design.
